THE MORRIS PETERS CO., WASHINGTON, D. C.

UNITED STATES PATENT OFFICE.

JOHN W. McMANAMA, OF WALTHAM, MASSACHUSETTS, ASSIGNOR TO BOSTON SAFETY SWITCH COMPANY, OF BOSTON, MASSACHUSETTS, A CORPORATION OF MAINE.

SAFETY APPLIANCE FOR RAILWAY-SWITCHES.

966,848.

Specification of Letters Patent. Patented Aug. 9, 1910.

Application filed May 9, 1908. Serial No. 431,847.

To all whom it may concern:

Be it known that I, JOHN W. McMANAMA, of Waltham, in the county of Middlesex and State of Massachusetts, have invented certain new and useful Improvements in Safety Appliances for Railway-Switches, of which the following is a specification.

This invention relates to a two-point railway switch, comprising fixed rails and a pair of movable switch rails or points which are connected to move in unison, means being employed for moving the switch rails to open and close the switch.

As explained in my Patent No. 876,577, granted January 14, 1908, it not infrequently happens that a switchman fails to fully throw the switch, and leaves the movable switch rails or points slightly separated from the inner sides of the fixed track rails between which they are located, the separation between the switch rails and the fixed rails being sufficient to permit the flanges of wheels of an engine or car approaching the switch, to run between the points of the switch rails and the adjacent inner sides of the fixed rails, the result being the derailment of the wheels, this derailment being often attended with serious damage.

The particular object of my present invention is to provide an improvement in the structure described and claimed in my said patent, which improvement will result in favoring the main line of the railway. It is known of course that trains more frequently use the main line than the branch track portion, and pass the switch at a much greater speed when running on the main line than when it is intended that the train shall be switched off to the branch line. In my present structure, therefore, I have provided means whereby the continuation of the main line is insured by a movement of the push bar in a direction toward the switch, which is the direction in which the train will be traveling, all as will be more fully pointed out hereinafter.

The invention consists in the construction and combination of parts substantially as hereinafter described and claimed.

Of the accompanying drawings in which similar reference characters indicate the same or similar parts, Figure 1 represents a top plan view of a portion of the railway track including a switch and a safety appliance embodying my invention, the switch

being shown in its closed position with the main track continuous. Fig. 2 represents a side elevation of one of the fixed rails and the safety appliance embodying my invention associated therewith, the push bar hereinafter described being in the position which it would occupy when the switch points are in the position shown in Fig. 1. Fig. 3 is a view similar to Fig. 2 but showing the push bar in the position which it occupies when the switch has not been completely thrown to the position shown in Fig. 1. Fig. 4 is a view similar to Fig. 1 but showing the branch line as open. Fig. 5 is a view similar to Fig. 2, but showing the push bar in the position which it occupies when the switch points are in the position shown in Fig. 4. Fig. 6 is a detail elevation of the bell crank lever operating mechanism. Fig. 7 is a view similar to Fig. 3 but illustrating another form of guide for the movements of the push bar.

In the drawings, 12 12 represent the fixed track rails, and 13 13 the movable track rails or switch points constituting the usual two-point switch, the switch rails 13 being adapted to occupy the position shown in Fig. 1 to make the main track continuous, and the position shown in Fig. 4 to connect the main track with a branch. The switch rails 13 are connected and caused to move in unison by a cross bar 14, and are moved by suitable mechanism which, as here shown, includes a switch lever 15 connected with a vertical rock shaft, which is connected by a link 16 with the cross bar 14. The construction above referred to is common and well known, and is here shown for the purpose of illustrating my invention hereinafter described.

The push bar 17 is located beside one of the fixed rails 12 as shown and described in my patent aforesaid, the same being capable of moving endwise and of being given a rising and falling movement as a result of its endwise movement, the arrangement being such that, when the push bar is at either extreme of its movement, its upper edge is substantially flush with the tread of the rail 12 beside which it is located, as shown in Fig. 2. Said push bar is supported by links 18 pivoted at 19 to fixed supports, said links being pivoted at 20 to the push bar. The location of the pivotal supports 19 relatively to the pivots 20, when the push bar is to occupy the position shown in Fig. 2 and to

maintain the main track continuous, is at the rear or away from the actual switch points, so that the links 18 incline upwardly and forwardly as clearly shown in Fig. 2. The 5 reason for this will be presently described.

The casting 26 has a base, the under side of which is formed to rest upon a flat-topped tie or other suitable support, and to be secured thereto. An upright portion of said 10 casting has its upper surface formed with a groove to receive a rib on the under side of an arm 27 which is removably secured in the position shown in Fig. 6. The rib and groove interlock to keep the arm from swinging. The casting base and the outer end of said arm 27 are formed with recesses in alinement to receive the trunnions 23 of a hub 21 of an arm 22. Said hub 21 also has an adjustable arm 220. This construction 15 provides for conveniently locating and setting up the switch operating device, and is durable and strong.

A rod or link 24 connects the push bar 17 with the outer end of the long arm 22, and 20 the link 25 connects the outer end of the short and adjustable arm 220 to the cross bar 14. Practically the arms 22 and 220 connected to the hub 21 constitute a bell 25 crank lever. The arm 220 in the form illustrated, is adjustable by reason of its being screw-threaded and fitting a threaded opening in the hub 21. This enables a nice adjustment to be effected to insure the proper height for the push bar 17 when the main 30 line of the railway track is closed or continuous.

It will now be understood that, if the switch has been incompletely thrown so that the push bar is slightly elevated above the 35 rail 12 as indicated in Fig. 3, an engine approaching at a high rate of speed and moving in the direction of the arrow in said Fig. 3, will be certain to move the push bar forward and downward, and do it easily regardless of the speed of travel, owing to the 40 fact that the movement, which it is desired shall be imparted to the push bar, is almost in the same direction as that in which the train is moving. This is due to the fact that 45 the pivots 19 for the links 18 are at a greater distance from the switch points than the pivots 20 when the push bar is in the position which it must occupy when the switch points render the main track continuous or 50 nearly so. Of course when the branch track is to be used, the switchman throws the lever 55 in a direction so as to shift the switch

points to or toward the position shown in Fig. 4. If he fails to completely throw the switch, the push bar will occupy a position 60 slightly above that shown in Fig. 5. The pivot points 20 are now at a greater distance from the switch points than the pivots 19 so that a movement of the push bar to complete the throwing of the switch must be 65 somewhat rearward as well as downward relatively to the direction of movement of the train. But since the train will always, or should be always at a lesser speed when approaching the branch track, the wheels of 70 the locomotive will not fail to depress the push bar 17 downward and backward so as to complete the throw of the switch points to their extreme position for directing the train on to the branch track. 75

The construction of the casting 26 which is bolted or otherwise secured to a tie or other suitable base, and the removable cap 27 enables the bell crank lever, consisting of the hub 21 and arms 22 and 220, to be readily 80 placed in position or removed when it is desired to change the adjustment of the arm 220, or for other purposes.

Instead of the links which serve as guides to control the path of movement of the push 85 bar from one extreme to the other, I may employ fixed plates 180 having slots 181 which receive and guide pins 182 projecting from the push bar 17.

I claim:—

In a railway switch, in combination, a single track, a branch including movable switch members, a longitudinally and vertically movable push bar located beside one of the rails of the single track portion, a 90 casting having a base formed to rest upon and be attached to a flat-topped support and having an upright portion, an arm removably secured to said upright portion and having a portion interlocking therewith, said 95 arm and base having recesses in alinement, a hub having trunnions mounted in said recesses and having a long arm and a shorter arm, the latter being adjustable, a link connecting said long arm and push bar, and 100 connections between said movable switch members and the adjustable arm of the said hub. 105

In testimony whereof I have affixed my signature, in presence of two witnesses.

JOHN W. McMANAMA.
